[57] ABSTRACT

A hydraulic cylinder operating in the tensile mode moves a scenery bar by means of a pulley system. The movement of a cylinder rod of the hydraulic cylinder is conveyed by means of a cable to a drum. The drum turns a lead screw, which moves a travelling nut along a keyway. A pointer attached to the travelling nut indicates the position of the cylinder rod and consequently the height of the scenery bar. Abutment of the travelling nut against a height stop moves a control rod which returns a manual control lever to its off position when a pre-set height is reached. The speed of raising or lowering the scenery bar can also be pre-set.

APPARATUS FOR MOVING SCENERY

The invention relates to apparatus for operating stage or television scenery, and more particularly relates to hydraulic apparatus for raising or lowering a piece of scenery for instalment in the "fly gallery" of a theatre. This is a gallery typically about 35 ft. from the floor on the stage and is hidden from the view of the audience. Apparatus for raising or lowering scenery bars to which are attached various pieces of scenery are conventionally operated by men in these fly galleries, using, for example, systems of pulleys and counterweights.

A conventional method of raising or lowering scenery is to load counterweights on to one end of the pulley system, balancing a scenery bar carrying an item of scenery at another end of the pulley system. This process of adding and removing weights in a small gallery above the stage is a difficult, slow and dangerous process.

Hydraulic mechanisms for moving scenery are also known comprising a hydraulic ram and a pulley system for moving a scenery bar carrying a piece of scenery. A known mechanism comprises a hydraulic ram having a vertically acting cylinder rod operating a pulley system, pulley sheaves being arranged above and below the ram. This means that a compressive load is applied to the rod, which must consequently be of substantial construction, with the concomitant disadvantages of extra weight and cost. It will be appreciated that cost is an important factor in this field, as it may be necessary to have provision for raising and lowering as many as 70 different items of scenery in a single theatre.

Another known mechanism comprises a double-acting hydraulic cylinder. A piston is moved hydraulically within the cylinder, and motion is transmitted from the piston to the pulley system by means of a steel-cored nylon cable.

It is desirable to be able to control the speed at which an item of scenery is moved and the height at which it is to come to rest. This can be done manually, but this involves a large number of skilled operators. Another possibility is to control the movement of the scenery electronically from a central consol. However, in this case, the control becomes overcentralised. Operators must still be provided in the fly gallery to prevent such problems as different items of scenery becoming tangled with or interfering with each other (this is conventionally done by means of long poles), but these operators are completely divorced from the central control system. Another difficulty is the cost of the electronic system. If, in order to overcome the disadvantage just referred to, i.e. overcentralisation of control, individual electronic systems are provided for the operators in each fly gallery, then the cost becomes prohibitive. Moreover, it has been found that the use of electronic systems requires considerable training.

In a preferred embodiment of the invention, a hydraulic cylinder operating in the tensile mode is arranged on a fly gallery and is connected to a pulley system to raise or lower an item of scenery movement of a cylinder rod of the said hydraulic cylinder being conveyed by means of a cable to a drum which rotates a lead screw, the lead screw being provided with a travelling nut which is made to move along the lead screw when the lead screw rotates; rotation of the nut being prevented by a keyway, the nut being provided with a pointer moving along a scale to indicate the height of

the item of scenery; supply of pressure fluid to the hydraulic cylinder being controlled by a manually operable control lever which is releasably connected to a control rod, the control rod being provided with pre-settable height stops, whereby when the travelling nut abuts one of the stops, the scenery item having reached a predetermined height, the nut moves the stop and consequently the control rod, thereby returning the control lever to its off position; means being provided for varying the position on the control rod at which the control lever is linked thereto, whereby the control lever can be pre-set at a given speed of the scenery item.

An advantage of the present invention is that, since the hydraulic cylinder is operating in the tensile mode, the cylinder and cylinder rod can be made much lighter than would be otherwise possible, i.e., if they were subjected to compressive loads. Another advantage is that the whole structure is more stable, and the means required to hold the cylinder can be of simpler and more economical design. For example, the cylinder may be held by a single pivot attachment point at its lower end, it being unnecessary to provide means for restraining rotation about the pivot.

A further advantage is that the pre-settable height stops can be set so that when a predetermined height is reached by the scenery item the control lever is automatically returned to its off position. It is also possible to pre-set the height which the scenery item is to reach and the speed at which it is to reach the set height. A number of scenery items can be pre-set in this way, and then all moved simultaneously in the pre-set manner by turning on a common hydraulic power supply. This is an important advantage when it is remembered that there may be from 50 to 100 different scenery items to be operated in a given theatre, and a substantial proportion of these may need to be operated during a 5 minute interval between acts. It is possible, for instance, for the speeds and heights of the various scenery elements to be set during the course of an act without actually moving them while the play or entertainment is in progress. However, during the interval, they can all be moved at the required rate to the required positions by operating a single button or switch, (i.e., the hydraulic power supply).

A further advantage of the invention is that if a scenery element is brought to rest by abutment of the travelling nut against one of the height stops, it is brought to rest gradually, as the control lever is gradually returned to its off position. This is important in that it prevents sudden strains being applied to the apparatus and scenery.

According to the invention there is provided an apparatus for raising or lowering an item of scenery in a theatre, comprising a vertical hydraulic cylinder having a cylinder rod extending from the upper end thereof, the cylinder rod being operatively connected to a pulley system arranged above said rod, said pulley system being adapted to raise or lower an item of scenery; said hydraulic cylinder being operated by pressure fluid, supply of said fluid being controlled by a valve having a manually operable control lever; fluid being supplied to the cylinder when the lever is in a first position thereof, no fluid being supplied when the lever is in a second position thereof, and fluid being allowed to drain from the cylinder when the lever is in a third position thereof beyond said second position; the rate at

which fluid is supplied to or allowed to drain from the cylinder when the lever is in any position intermediate the said first and second positions being dependent on the proximity of said intermediate position to the first or second position; the apparatus further comprising a control rod movable in the axial direction of said rod; releasable means being provided for operatively connecting said control lever to said control rod, whereby when said lever and said rod are operatively connected, the control rod moves in its axial direction in response to movement of the control lever and the control lever is moved by movement of the control rod; the releasable means being adapted to connect the control lever to the rod at a range of different positions on the rod, whereby while said control rod is stationary, the lever can be set at a predetermined position to allow pressure fluid to be supplied to or drained from the hydraulic cylinder at a selectable predetermined rate; the apparatus being further provided with a rotatable drum having a cable wound round it, the cable being connected to the cylinder rod, whereby motion of the cylinder rod rotates the drum; a lead screw rotated by rotation of the drum; the lead screw having a travelling nut moved along the lead screw by rotation of the lead screw; pre-settable height stops settable at selectable positions on the control rod; the lead screw being arranged parallel to the control rod, whereby the travelling nut moves along the lead screw until it abuts one of said height stops, thereby moving the control rod and returning the lever to its second position, wherein no fluid is supplied to the cylinder, thereby stopping an item of scenery attached to said pulley system at a selectable predetermined height.

The invention will be further described with reference to the accompanying drawings, which illustrate an embodiment of the invention, which is given by way of example only and not by way of limitation.

In the drawings:

FIG. 1 is a side view of a mechanism constituting an embodiment of the invention, the hydraulic system not being shown;

FIG. 2 is a diagrammatic view of the hydraulic system of the mechanism of FIG. 1;

FIG. 3 is a plan view, with the cover removed of the control box of the mechanism of FIG. 1, with two scrap views of the top of the cover;

FIG. 4 is a section through the control box along the line AA';

FIG. 5 is a section through the control box along the line BB'; and

FIG. 6 is a detail showing the bevel gear drive of a rotary pointer on the control box.

A hydraulic ram 1, having a cylinder rod 2 is mounted vertically on a wall 3 just above a fly gallery floor by means of a cylinder mounting bracket 4. The cylinder rod 2 carries at its end a first rope sheave 5 and a second rope sheave 6. A sheave mounting bracket 7 attached to the wall 3 near the roof 8 has mounted thereupon a third sheave 9, a fourth sheave 10 and a rope anchor 11. Each of the sheaves 5, 6, 9 and 10 has at least four peripheral groups which accommodate four ropes 11a, 11b, 11c, and 11d, each of which is secured at one end to the rope anchor 11, passes down to sheave 5, round it, then up to sheave 9, round it, down to sheave 6, round it, up to sheave 10 and there to the respective grid sheave assembly 12a, 12b, 12c or 12d, and then down to a scenery element, shown as scenery

bar 13, to which their other ends are secured. The grid sheave assemblies 12a, 12b, 12c and 12d are rotatably held in grid 14 which is fixed to roof 8 of the theatre. The pulley system is constituted by sheaves 5, 6, 9 and 10, held by members 2 and 7 respectively together with ropes 11a, 11b, 11c and 11d and grid sheave assemblies 12a, 12b, 12c and 12d held by grid 14.

The velocity ratio of the pulley system is 4. This is because the fly gallery is ordinarily half way between the floor and the ceiling of the theatre, and, with this particular type of hydraulic cylinder arrangement only half of the height from the fly gallery to the ceiling is available for the stroke of the ram. The scenery bar must, however, be able to move the full height of the theatre.

15 The provision of a plurality of ropes attached to a plurality of points of scenery bar 13 enables the bar 13 to be maintained horizontal while being raised or lowered, and also enables it to be easily brought close to the grid 14.

20 Ram 1 is provided with a space 18 which is hydraulically connected, via conduit 26 to a check valve 27, which is in turn connected hydraulically via conduits 24 and 25 to a four-way spool type directional valve 28 operated by a control linkage 22. Valve 28 is further hydraulically connected to pressure line 33 and return line 19. More than one hydraulic cylinder, with its associated check valve, spool valve and control, may be connected to the pressure line and return line. Control linkage 22 is in turn linked to a control lever 34 by

25 means of a crank 35. Thus when pump 60 is switched on, and the valve member is in its left-hand position in FIG. 2, pressure fluid is delivered to space 18 of hydraulic ram 1, causing cylinder rod 2 to be lowered and scenery bar 13, with the scenery normally attached thereto, to be raised by a corresponding but magnified amount. In this case the control lever 34 is in its extreme lower position X in FIG. 5.

In FIG. 2, 101 is a tank, 102 is a filter, 103 is a pressure relief valve, 104 is an acoustic filter, 105 is a check valve, 106 is a fluid accumulator, 107 is a pilot operated unloading valve, 108 is a solenoid operated shut off valve. The function of these members 101 to 108 will not be described in detail, since these are known components connected in a conventional manner to provide a pressure fluid supply to pressure line 33 and a return via return line 19. These components form a power pack which is remotely located in a machinery room.

50 When lever 34 is in its position Z, the valve member is in its extreme right-hand position and fluid is allowed to drain from space 18 and the scenery bar 13 is lowered. The pressure supplied via conduit 25 to check valve 27 acts to open the valve to allow pressure fluid to drain from space 18. The rate at which fluid is supplied to or allowed to drain from the space 18 is determined by the proximity of lever 34 to its extreme end positions X and Z. The weight of scenery bar 13 is sufficient to force fluid from space 18, so that lowering takes place under gravity. In the intermediate position Y of the lever, no fluid is supplied to or drained from the space 18 and bar 13 remains stationary.

Control box 32 comprises a cylindrical drum 35 on which a cable 29 is wound. Cable 29 is secured at one end thereof to a tensioning spring 30 and passes round to small sheaves 31 until it reaches the drum, whereafter it returns, by means of sheaves 31 and is secured at its other end to member 36 which is fixed to rod 2 and

to the other end of spring 30. Thus motion of rod 2 is transmitted by cable 29 and rotates drum 35.

Drum 35 is rigidly connected to lead screw 37 so that rotation of drum 35 rotates screw 37. Nut 38 is prevented from rotating by keyway 39 engaging slot 40 of the nut and is therefore driven up or down the lead screw when the drum is rotated by movement of the cylinder rod. The arrangement is such that the nut moves up when the scenery bar is moved up and down when the scenery is moved down. A pointer 41 attached to the nut indicates the position of the nut and consequently the height of the scenery bar with the aid of a linear scale 42 on the cover of the control box. A rotary pointer 43 is driven by a bevel gear 44 at the end of the lead screw and moves on a circular scale 45 on the cover of the control box to provide a finer indication of the height of the scenery bar. In this example, the linear scale is calibrated in feet and the circular scale in inches, the gear ratio of the bevel gear being such that movement of the scenery through 12 inches rotates the rotary pointer once.

The control lever 34 passes through a collar 46 fixed to a control rod 47 by means of a screw 51 at an adjustable position. In other words, the collar can be moved up or down the control rod and secured in a desired position. Thus motion of the control lever moves the control rod and vice versa. The control rod is movable in the direction of its axis, but is prevented from rotating by a key 48. A spring centering device 49 is provided at the end of the control rod remote from the control lever, the spring of the spring centering device being stronger than the spring of the hydraulic valve. As already explained, the degree of opening of the hydraulic valve, and consequently the speed at which the scenery bar moves, is controlled by the position of the control lever. The control lever moves over the quadrant scale 50 which is graduated to indicate the speed of the scenery bar.

The control rod is provided with upper and lower presettable height stops 53 and 54 respectively, each comprising an adjustable screw 55 or 56 respectively running in a slot 52 of the control rod and also comprising a sliding block 57 or 58 respectively.

The control box is operated as follows.

If all three adjusting screws are loose the control lever can be operated manually in the normal way. During a rehearsal, the scenery bar is lowered or raised to the required position.

The required height can then be pre-set by means of one of the height stops, while the speed at which the item of scenery is to move is pre-set by securing the collar to the control rod. The actual speed can be read from the quadrant scale. It will be noted that this manner of pre-setting the height and speed requires no special training, since the operator will already have the "feel" of the control lever by manual operation. Upper and lower height stops are provided so that an item of scenery can be moved from a pre-set starting height to a pre-set final height.

What I claim is:

1. Apparatus for raising or lowering an item of scenery in a theatre, comprising a hydraulic cylinder operatively connected to a pulley system, said pulley system being adapted to raise or lower an item of scenery; said hydraulic cylinder being operated by pressure fluid, supply of said fluid being controlled by a valve having a manually operable control lever; fluid being supplied

to the cylinder when the lever is in a first position thereof, no fluid being supplied when the lever is in a second position thereof, and fluid being allowed to drain from the cylinder when the lever is in a third position thereof beyond said second position; the rate at which fluid is supplied to or allowed to drain from the cylinder when the lever is in any position intermediate the said first and second positions being dependent on the proximity of said intermediate position to the first or second position; the apparatus further comprising a control rod movable in the axial direction of said rod; releasable means being provided for operatively connecting said control lever to said control rod, whereby when said lever and said rod are operatively connected, the control rod moves in its axial direction in response to movement of the control lever and the control lever is moved by movement of the control rod; the releasable means being adapted to connect the control lever to the rod at a range of different positions on the rod, whereby, while said control rod is stationary, the lever can be set at a predetermined position to allow pressure fluid to be supplied to or drained from the hydraulic cylinder at a selectable predetermined rate; the apparatus being further provided with a rotatable drum having a cable wound round it, the cable being connected to the pulley system, whereby motion of the pulley system rotates the drum; a lead screw rotated by rotation of the drums; the lead screw having a travelling nut moved along the lead screw by rotation of the lead screw; presettable height stops settable at selectable positions on the control rod the lead screw being arranged parallel to the control rod, whereby the travelling nut moves along the lead screw until it abuts one of said height stops, thereby moving the control rod and returning the lever to its second position, wherein no fluid is supplied to the cylinder, thereby stopping an item of scenery attached to said pulley system at a selectable predetermined height.

2. Apparatus for raising or lowering an item of scenery in a theatre, comprising a vertical hydraulic cylinder having a cylinder rod extending from the upper end thereof, the cylinder rod being operatively connected to a pulley system arranged above said rod, said pulley system being adapted to raise or lower an item of scenery; said hydraulic cylinder being operated by pressure fluid, supply of said fluid being controlled by a valve having a manually operable control lever; fluid being supplied to the cylinder when the lever is in a first position thereof, no fluid being supplied when the lever is in a second position thereof, and fluid being allowed to drain from the cylinder when the lever is in a third position thereof beyond said second position; the rate at which fluid is supplied to or allowed to drain from the cylinder when the lever is in any position intermediate the said first and second positions being dependent on the proximity of said intermediate position to the first or second position; the apparatus further comprising a control rod movable in the axial direction of said rod; releasable means being provided for operatively connecting said control lever to said control rod, whereby when said lever and said rod are operatively connected, the control rod moves in its axial direction in response to movement of the control lever and the control lever is moved by movement of the control rod; the releasable means being adapted to connect the control lever to the rod at a range of different positions on the rod, whereby, while said control rod is stationary, the lever

can be set at a predetermined position to allow pressure fluid to be supplied to or drained from the hydraulic cylinder at a selectable predetermined rate; the apparatus being further provided with a rotatable drum having a cable wound round it, the cable being connected to the cylinder rod, whereby motion of the cylinder rod rotates the drum; a lead screw rotated by rotation of the drum; the lead screw having a travelling nut moved along the lead screw by rotation of the lead screw; pre-settable height stops settable at selectable positions on the control rod; the lead screw being arranged parallel to the control rod, whereby the travelling nut moves along the lead screw until it abuts one of said height stops, thereby moving the control rod and returning the lever to its second position, wherein no fluid is supplied to the cylinder, thereby stopping an item of scenery attached to said pulley system at a selectable predetermined height.

3. Apparatus as claimed in claim 2, wherein the control rod is provided with a spring centering device, and the pressure fluid supply valve is provided with a centering spring, the spring of the spring centering device of the control rod being stronger than the spring of the pressure fluid supply valve.

4. Apparatus as claimed in claim 2, wherein the travelling nut is provided with a pointer to indicate the height reached by the scenery element.

5. Apparatus as claimed in claim 2, wherein the end of the lead screw drives a rotary pointer to indicate subdivisions of height attained by the scenery element.

6. Apparatus as claimed in claim 2 wherein said vertical hydraulic cylinder is mounted in a fly gallery of the theatre and includes a piston defining upper and lower spaces in said hydraulic cylinder, and wherein said pulley system has a velocity ratio of 4, with fluid being supplied to said upper space of said cylinder when the manually operable control lever of said valve is in said first position, no fluid being supplied when said lever is in said second position, and fluid being allowed to drain from said upper space of said cylinder when the lever is in a third position beyond said second position, with the rate at which fluid is supplied to or allowed to drain from said cylinder when the lever is in any position intermediate said first and second positions being dependent on the proximity of said intermediate position to the first or second position.
